UNITED STATES PATENT OFFICE.

JOHN R. PRING, OF SHAWNEE, OKLAHOMA, ASSIGNOR OF ONE-HALF TO WILLIAM N.
HURT, OF SHAWNEE, OKLAHOMA.

OIL-BURNER.

1,064,251.

Specification of Letters Patent. Patented June 10, 1913.

Application filed August 1, 1912. Serial No. 712,710.

To all whom it may concern:

Be it known that I, JOHN R. PRING, a citizen of the United States, residing at Shawnee, in the county of Pottawatomie 5 and State of Oklahoma, have invented certain new and useful Improvements in Oil-Burners; and I do declare the following to be a full, clear, and exact description of the invention, such as will enable others skilled 10 in the art to which it appertains to make and use the same.

This invention relates to improvements in oil burners.

One object of the invention is to provide 15 a burner of this character having an improved construction and arrangement of heating and gas generating coil, whereby the oil passing therethrough will be thoroughly heated and converted into gas before 20 being discharged from the burner.

Another object is to provide an improved 25 construction and arrangement of flame spreader whereby the flame may be deflected downwardly or forwardly to a greater or less extent, as desired.

With these and other objects in view, the 30 invention consists of certain novel features of construction, and the combination and arrangement of parts as will be more fully described and claimed.

In the accompanying drawings: Figure 1 is a perspective view of one of my improved 35 gas generating burners; Fig. 2 is a horizontal sectional view through a fire box and a portion of a stove showing two of my improved burners applied thereto; Fig. 3 is a vertical cross sectional view thereof; Fig. 4 is a central vertical cross sectional view 40 through one of the burners showing in full and dotted lines the manner in which the flame deflecting spreader is adjusted to deflect the flame forwardly or rearwardly, as desired; Fig. 5 is a detail perspective view of one of the flame spreaders removed from 45 the burner; Fig. 6 is a similar view of the gas starting pan in which the oil is burned for the preliminary heating of the coil.

My improved burner comprises a pipe 1 which is bent to form an upper horizontal 50 tube 2, laterally projecting oppositely disposed side tubes 3, and a horizontally projecting tube 4, which is disposed immediately below and spaced a suitable distance from the upper tube 2. The end of the tube 55 4 is closed, and in the upper side thereof is

a centrally disposed gas opening 5 through which the gas escapes and burns. The outer end of the pipe 1 is adapted to be connected with an oil conducting pipe 6 projecting from the stove and leading to an oil reservoir 7 or other source of supply. In the pipe 6 is arranged an oil controlling or cut-off valve 8, whereby the flow of the oil to the burner is controlled.

Loosely connected to and hanging pendant from the lower tube 4 of the burner is a generating pan 9, which is preferably of oblong shape, and extends from one end to the other of the tube 4 as shown. The ends of the pan are extended upwardly to form supporting lugs 10 which are apertured to receive the tube 4, whereby the pan is supported on or hangs from said tube in position to receive the priming charge of oil which is permitted to run into the pan from the burner opening 5, and which is ignited and burns in the pan, primarily heating the coil and turning the oil therein into gas, which, when ignited at the burner spreader will continue to heat the coil so that the oil flowing therethrough will be thoroughly converted into gas before being discharged from the burner opening.

Arranged above the lower tube 4 and the burner opening therein is a flame spreader 11, whereby when the gas from the opening 5 is ignited, its flame will be spread and caused to come into contact with the side members of the burner tube, and whereby the flame may be deflected rearwardly or forwardly, as desired. The spreader 11 comprises a flat disk 12, which is preferably of circular shape, and has formed on its upper side a supporting lug 13 having in its lower portion a transverse opening 14 to receive the upper tube of the pipe 1 on which said spreader is pivotally supported.

To the upper end of the lug 13 is pivotally connected the inner end of an adjusting rod or lever 15 which extends downwardly through one side of the fire box and is provided on its outer end with an operating handle 16. On the rod 15 is arranged a rack 17, the teeth of which are adapted to be engaged with the lower edge of the slot 18 in the side of the stove through which the rod passes. By pivotally supporting the spreader and providing the adjusting rod 15, it will be seen that the spreader may be rocked or tilted in one direction or the other to deflect

the flame from the burner opening toward the rear portion of the stove, as desired, and by means of the rack 17 on the lever the spreader may be held in its adjusted position.

5 By constructing my improved burner as herein shown and described, it will be seen that it may be readily applied to a heating or cook stove or furnace, and when applied to a cook stove, two or more of the same may 10 be arranged in the fire box thereof, as shown in Fig. 2 of the drawings.

It will be noted that by providing each burner with an oil controlling valve 8, one or both of the burners may be used.

15 From the foregoing description, taken in connection with the accompanying drawings, the construction and operation of the invention will be readily understood without requiring a more extended explanation.

20 Various changes in the form, proportion and the minor details of construction may be resorted to without departing from the principle or sacrificing any of the advantages of the invention as claimed.

25 Having thus described my invention, what I claim is:

1. An oil burner comprising a pipe bent to form a coil, said coil having upper and lower horizontally disposed tubes and laterally projecting side tubes connected therewith, a generating pan secured to and supported by said lower tube, a flame spreader

pivotal secured to the upper tube, a spreader adjusting lever pivotally connected to the spreader, and means on said lever whereby the latter may be locked to hold the spreader in its adjusted position.

2. The combination with a stove having an opening of an oil burner comprising a pipe bent to form an oil heating and gas generating coil having upper and lower horizontally disposed tubes, and laterally projecting side tubes connected therewith, said lower tube having therein a burner opening, a flame spreader comprising a disk having thereon an apertured lug whereby the same is pivotally connected to said upper tube over the burner opening in the lower tube, a spreader adjusting rod pivotally connected at its inner end to said lug and adapted to project through said opening in the stove, and a rack arranged on the outer end of the rod adapted to engage one edge of the opening in the stove, whereby the rod is locked and the spreader held in its adjusted position.

45 30 35 40 45 50 55 In testimony whereof I have hereunto set my hand in presence of two subscribing witnesses.

JOHN R. PRING.
